COPY AND BOOK HOLDER

Mabelle M. Hunt, Los Angeles, Calif.

Application March 1, 1933, Serial No. 659,077

14 Claims. (Cl. 120—33)

This invention relates to a typewriter's copy-holder such as used by typists for holding copy that is being transcribed on a typewriter.

The general object of the invention is to produce a device for this purpose, of simple construction, which can be employed to support a book when it is being copied from, and which can also be readily used to support sheets of manuscript, at the same time providing a line-marker to be advanced down the sheet as the copying progresses.

One of the objects of the invention is to provide a simple means for operating the line-marker from a point within convenient reach of the typist.

A further object of this invention is to improve the general construction of devices of this type.

Further objects of the invention will appear hereinafter.

The invention consists of the novel parts and combination of parts to be described hereinafter, all of which contribute to produce an efficient copy and book holder.

A preferred embodiment of the invention is described in the following specification, while the scope of the invention is pointed out in the appended claims.

In the drawing:

Figure 1 is a front elevation of a copy-holder embodying my invention, certain parts being broken away.

Figure 2 is a vertical section through the copy-holder, taken on the line 2—2 of Figure 1, and this view also illustrates two sheets of loose copy supported in the device. In this view, a portion of the operating arm is broken away to save space.

Figure 3 is a plan and section taken about on the line 3—3 of Figure 2. In this view in dotted lines is illustrated a book held on the bookrest.

Figure 4 is a detail, and is a vertical section taken through the upper left-hand corner of the frame of the device, and particularly illustrating the manner in which the operating cord is guided around the corners of the frame.

Figure 5 is a vertical section taken about on the line 5—5 of Figure 3, certain parts being broken away.

Figure 6 is a vertical section taken on the line 6—6 of Figures 2 and 5, and further illustrating details of the means for controlling the cord that actuates the line-marker.

Referring more particularly to the parts, 1 indicates the frame of the device, which is of a

substantially rectangular form in front elevation, as shown in Figure 1. This frame comprises a pair of oppositely disposed posts 2 and 3, which are preferably of tubular form, and connected together below by a tie bar 4, and carrying feet 5 or other suitable means for enabling the frame to rest upon a table or desk, in an upright position.

At a sufficient height to enable the copy to be visible over a typewriting machine, the frame 10 is provided with a rigid cross bar 6, which rigidly connects two sleeves 7, which are rigidly secured on posts 2 and 3, and on this cross bar 6 a book-rest 8 is supported, which is preferably in the form of a horizontal frame, presenting a plurality of 15 horizontal bars 9, 10, and 11, which extend rearwardly from the main frame 1. In addition to this, I prefer to provide a second rigid cross bar 12, which operates as a stop for the forward and lower edge of an open book such as the book 13, 20 indicated in dotted lines in Figure 3. On the bars 9, 10, and 11, I provide bookholders 14, 15, and 16. The bookholder 14 is on the middle bar 10, and is preferably longer than the others. These bookholders are stout bars that project 25 upwardly, each bar having an enlarged head 17 at its lower end, which has a square opening 18 through it to enable it to slide on its bar. The upper and forward faces of the bookholders are preferably provided with light bow springs 19 30 that exert a yielding pressure against the back of the book.

Guided to move up and down on the posts, I provide a line-marker 20. This line-marker is preferably attached to an elongated head 21 that 35 runs in the bore of one of the posts, for example, the post 3, and this post is formed with a longitudinal slot 22 (see Fig. 3), through which the line-marker 20 extends. The other end of the line-marker is guided in a slot formed between 40 two parallel guides 23 formed on the inner face of the opposite post 2. I provide means for urging the line marker in an upward direction. In the present instance the line-marker 20 is supported on a cord 24 that is attached to the head 45 21 of the line-marker, and which is guided within the frame. The upper portion of this cord passes around guide pulleys 25 and 26, which are mounted at the upper end of the frame and opposite to a tubular cross bar 27 through which the cord 50 extends in passing over to the other side of the frame, at which point the cord is attached to a counterweight 28 that can run up and down freely in the post 2. This counterweight holds the cord in tension and keeps the line-marker 20 in 55

position. The pulleys 25 and 26 are mounted in suitable elbow brackets 29 (see Fig. 4), and at these brackets small guide openings 30 are provided, which guide the cord and keep it in position on the pulleys.

In order to enable the line-marker to be operated from a convenient point near the front of the typewriting machine, and to one side of the same, I provide the lower end of the post 3 with a side arm 31, which is preferably of tubular form, and which normally extends out in a forward direction from the post 3. This arm is preferably mounted so that it can fold into the plane of the frame 1. For this purpose, it is preferably connected by two swivel joints 32 and 33, to upper and lower sections of the post 3. These joints may be formed by providing an elbow bracket 34 formed with an upwardly projecting hub 35 with a guide opening 36 through it for the cord. This hub fits neatly in the lower end of the tubing of the post, and is provided with a circumferential slot 37 to receive a set screw 38. The joint 33 is constructed in the same way, but of course, is devoid of any guide for the cord. In the elbow 34 a guide pulley 39 is mounted for the cord, the under side of which is in line with a guide opening 40 in a horizontal hub 41 to which the arm 31 is rigidly secured. At its outer end the arm 31 is provided with an elbow bracket 42 within which is mounted a spool 43, to which the end of the cord is attached so that it will wrap upon the spool. The spool 43 is provided at one end with means for rotating it at will. In the present instance, this means is a knurled wheel 44. Connected with the pulley, brake means is provided which resists the pull of the weight 28, so that the weight can not rotate the spool while the brake means is applied. Any suitable brake means may be employed, but in the present instance, this consists of a small pulley 45 rigidly attached to the spool and having a braking face in the form of a surface of revolution, preferably having a V-shaped groove 46 in it, in which a V-shaped portion 47 of a brake lever 48 has sliding contact. This brake lever is mounted on a pivot pin 49 toward the front, so that it projects back under the arm 31, and it is pressed up against the brake pulley 45 by a coil spring 50 housed in a tubular foot 51 that extends down from the elbow bracket 42, so that the end of this foot can rest upon the upper surface of the desk or table on which the device rests. The upper end of the spring 50 is received in a tubular cap 52 that thrusts against the under side of the lever (see Fig. 6), and this spring can be adjusted by means of an adjustable screw plug 53 that is threaded into the lower end of the tubular foot 51.

At the upper end of the frame, the copy-roller 54 is provided, that extends across the frame in a horizontal position, the said roller having a shaft 55 that is rotatably mounted on the posts 2 and 3, and the projecting end of the shaft is preferably provided with a handwheel 56 for rotating it at will. The sheets to be copied, such as the sheet 57, are clamped against this roller 54 by a clamping roller 58 which is parallel to it, and which is carried on the lower ends of two arms 59, which are rigidly secured to the cross tube 27 at the top of the frame. These arms extend upwardly and carry a cross bar 60 that operates as a handle for swinging the clamping roller 58 away from the copy-roller 54. Resilient means is provided for pressing the clamping roller against the copy-roller. Any suitable means may

be employed for this purpose, but in the present instance, I provide a coil spring 61 that may be housed in the end of one of the adjacent elbows, or as illustrated, in the tube 27. One end of this spring is secured as at 62, to the tube 27, and the other end is anchored as at 63, in the adjacent elbow bracket so that the tube 27, carrying the arms 59, may rotate with respect to the elbows 29.

On the cross bar 6, I mount presser means for 10 pressing against the open pages of a book, such as the book 13. This means is preferably in the form of two vertically extending flat bars 64, the lower ends of which are secured to the sleeves 65 in the form of blocks, which slide freely on the 15 bar 6. This bar 6 is of square cross section so as to hold the presser bars 64 upright. The upper ends of the presser bars 64 are preferably offset rearwardly as shown. Below the offset upper ends, these bars 64 lie near and just to the 20 rear of the line-marker 20, so that the manuscript copy such as sheet 57 can be held between the bars 64 and the line-marker.

If desired, the upper end of the frame may be provided with a horizontally extending bar 66, 25 which is located back of the frame and at a slightly lower level than the handle bar 60. This enables some of the copy sheets such as the sheet 67, to be hung over the handle bar 60, so that it hangs down in front of the bar 66. 30

This bar 66 may be connected by a transverse extension 68, with a cross bar 69 that extends across between the posts to which it is secured. This bar 69 lies near the plane in which the line-marker 20 moves when it slides up and down in 35 operation. In Fig. 2 the cross-bar 69 is indicated in dotted lines because it is back of the plane of the line 2-2 of Fig. 1 in which this section is taken.

The mode of operation of the device will now 40 be described. When employing the device for copying from a book, the book, such as the book 13, is set on the frame 8 in an open position, and the bookholders 14, 15, and 16 are shoved up behind the book to hold it securely in position with its 45 open pages in a substantially vertical plane. The presser bars 64 are then slid out toward the outer vertical edges of the pages, so as to hold them in position without obstructing the view of the text on the pages of the book. The line-marker 23 50 is then set to the line where the copying is to commence, and as each line is copied, the typist gives a slight rotation to the knurled wheel 44. In this way, the line-marker 20 can be moved down the page line by line as the copying 55 progresses.

By pressing down on the brake lever 48, the weight 28 will pull the line-marker 20 back to its most elevated position.

When copying from manuscript, the sheets of 60 the manuscript are clamped between the copy-roller 54 and the clamping roller 58. These rollers may be faced with rubber, if desired. The sheet being copied from, hangs down forward of 65 the pressers 64, and just back of the line-marker 20. These parts cooperate to hold the copy in reading position. As the sheets of the manuscript are finished, they can be folded back out of the way, as indicated in Figure 2.

When the copyholder is not in use, the arm 31 70 may be swung on the swivel joints 32 and 33, so that it extends across the frame 1 at its lower end. In this position, this arm will lie substantially in the plane of the frame 1.

I claim:

1. In a typewriter's copy-holder, the combination of a frame having a pair of posts located respectively on the right and left sides of the frame, 5 feet carried by the posts for holding the frame in a substantially vertical plane, an arm located on one side of the frame and extending substantially horizontally from one of the posts on the forward side of the frame, a spool freely rotatable in either direction, mounted in the said arm, a cord attached to the spool and wrapped thereupon, means for guiding the said cord up the post corresponding to the said arm, across to the opposite side of the frame and vertically downward at the 15 opposite post, a weight carried by the cord associated with the said opposite post, a line-marker attached to the cord, and means for resisting the rotation of the spool to hold the spool in any position in which it is left.
2. In a typewriter's copy-holder, the combination of a frame having a pair of oppositely disposed tubular side posts, means for holding the frame in a substantially vertical position, an arm having a joint connecting the same with one of 25 said posts enabling the arm to fold transversely against the frame and enabling it to be swung out to a substantially horizontal position projecting forwardly from the frame, a spool rotatably mounted in the said arm, means associated with the spool for rotating it, a cord attached to the spool and wrapped thereupon, means for controlling the rotation of the spool under the tension of the cord, means for guiding the cord up the post adjacent to said arm, across to the opposite 30 side of the frame and vertically downward within the opposite post, a weight carried by the cord within the opposite post, one of said posts having a longitudinal slot therein, and a line-marker attached to the cord within the last-named post and 35 extending out through the said slot.
3. In a typewriter's copy-holder, the combination of a frame having a pair of oppositely disposed tubular side posts, means for holding the frame in a substantially vertical position, an arm having a joint connecting the same with one of 40 said posts enabling the arm to fold transversely against the frame and enabling it to be swung out to a substantially horizontal position projecting forwardly from the frame, a spool rotatably mounted in the said arm, means associated with the spool for rotating it, a cord attached to the spool and wrapped thereupon, means for controlling the rotation of the spool under the tension of the cord, means for guiding the cord up the post adjacent to said arm, across to the 45 opposite side of the frame and vertically downward within the opposite post, a weight carried by the cord within the opposite post, one of said posts having a longitudinal slot therein, and a line-marker attached to the cord within the last-named post and 50 extending out through the said slot, and means for guiding the line-marker on the opposite post.
4. In a typewriter's copy-holder, the combination of a frame having a pair of tubular side posts, located respectively on the right and left side of the frame, means for holding the frame in a substantially vertical position, an arm attached to the frame and extending forwardly 55 from the same at one side, a spool rotatably mounted in the said arm, means associated with the spool for rotating it, a cord attached to the spool and wrapped thereupon, and means for guiding the cord up the adjacent post, across to 60 the other side of the frame and down the opposite

post, one of said posts having a longitudinal slot therein, a line-marker guided in said slot and attached to the cord, and a weight carried by the cord in the post opposite to the said arm.

5. In a typewriter's copy-holder, to be placed back of a typewriting machine, the combination of a frame, means for holding the same in a substantially vertical position, an arm extending forwardly from said frame, so as to project to a point near the front and side of the typewriting machine, a spool rotatably mounted on the arm, a cord guided in said frame and wrapped on the spool, a line-marker attached to the cord, and a weight attached to the end of the cord to maintain the cord taut, a brake-wheel associated with the spool, a brake-lever cooperating with the brake-wheel and projecting longitudinally under the said arm, and a spring for pressing the brake-lever against the brake-wheel, said brake operating to permit the hand-actuated means to rotate the spool, and prevent the weight from rotating the spool when the brake is applied.

6. In a typewriter's copy-holder, the combination of a frame including opposite substantially vertical posts, means for supporting the frame in a substantially vertical position, a book-rest for supporting an open book, secured to the rear side of the frame and comprising substantially horizontal members extending rearwardly from the frame, a book-holder corresponding to each of 25 said members and mounted for adjustment in a front and rear direction on the horizontal members, said book-holders projecting upwardly to engage the back of the book when supported in an open position, a line-marker guided on said frame to extend across the front of the open book, and means for raising and lowering the line-marker.

7. In a typewriter's copy-holder, the combination of a frame including opposite substantially vertical posts, means for supporting the frame in a substantially vertical position, a book-rest for supporting an open book, said book-rest rigidly secured to the rear side of the frame and comprising substantially horizontal members extending rearwardly from the frame, a book-holder corresponding to each of said members and mounted to slide thereon, said book-holders projecting upwardly to engage the back of the book when supported in an open position, a line-marker guided on said frame to extend across the front of the open book, presser means mounted on the frame for pressing against the leaves of the book, and means for raising and lowering the line-marker.

8. In a typewriter's copy-holder, the combination of a frame including opposite substantially vertical posts, means for supporting the frame in a substantially vertical position, a book-rest for supporting an open book, said book-rest rigidly secured to the rear side of the frame and comprising substantially horizontal bars extending rearwardly from the frame, a book-holder corresponding to each of said bars and mounted to slide thereon, said book-holders projecting upwardly to engage the back of the book when supported in an open position, a line-marker guided on said frame to extend across the front of the open book, presser means for pressing the open pages of the book to maintain them in reading position, clamping means at the upper end of the frame for supporting manuscript copy, said line-marker being disposed forwardly of the presser means so as to enable a page or pages of the manuscript copy to be held between the 70

presser means and the line-marker to maintain the manuscript copy in reading position, and means for raising and lowering the line-marker.

9. In a typewriter's copy-holder, the combination of a frame including opposite substantially vertical posts, means for supporting the frame in a substantially vertical position, a book-rest for supporting an open book, said book-rest rigidly secured to the rear side of the frame and comprising substantially horizontal bars extending rearwardly from the frame, a book-holder corresponding to each of said bars and mounted to slide thereon, said book-holders projecting upwardly to engage the back of the book when supported in an open position, a line-marker guided on said frame to extend across the front of the open book, presser bars for pressing the pages of the open book to hold the same in reading position, copy-holding means for holding manuscript copy at the upper end of the frame including a relatively fixed clamping bar and a spring-pressed movable clamping bar cooperating therewith to hold the manuscript copy in reading position between the presser bars and the line-marker, and means for raising and lowering the line-marker.

10. In a typewriter's copy-holder, the combination of an upright frame, means for supporting the frame in a substantially vertical position, said frame having a pair of side posts with slots on their adjacent sides, a line-marker guided in said slots, means for raising and lowering the line-marker, said frame having a transverse bar at a considerable elevation thereon, a pair of presser arms guided to slide on said transverse bar and extending upwardly therefrom to the rear of the line-marker, a copy-roller rotatably mounted in the upper part of the frame with means for rotating the same, and a spring-pressed clamping roller cooperating with the copy-roller for clamping copy with the sheets of copy hanging down in front of the presser bars and behind the line-marker, said rotating means comprising a hand wheel on the copy-roller for rotating the same.

11. In a typewriter's copy-holder, the combination of a frame including opposite substantially vertical posts, a book-rest supported on the rear side of the frame, presser means mounted on the frame to cooperate with the book-holder to press against the pages of an open book held on the book-rest, a copy-holder supported on the frame above the book-rest, having means for supporting copy so that it hangs in front of the said presser means, and a line-marker guided vertically on said frame in front of the presser means.

12. In a typewriter's copy-holder, the combination of a frame having a pair of posts located respectively on the right and left sides

of the frame, means for supporting the posts to hold the frame in a substantially vertical plane, a tubular arm located on one side of the frame and extending substantially horizontally from one of the posts on the forward side of the frame, and mounted on the post to swing on the axis of the post to enable the arm to swing back substantially into the plane of the frame, a spool rotatably mounted in the said arm at the forward end thereof, a cord attached to the spool and wrapped thereupon, said cord extending through said tubular arm into the adjacent post, a line marker attached to the cord, means for guiding the line marker on the post, means for urging the line marker upwardly, and means associated with the spool for controlling the same to enable the line marker to be moved progressively from an elevated position down the said frame.

13. In a typewriter's copy-holder to be placed at the back of a typewriting machine, the combination of a frame having a pair of posts located respectively on the right and left sides of the frame, a line marker guided on said posts, means carried by the posts for holding the frame in a substantially vertical plane, a side arm pivoted at the side of the frame projecting forwardly from the forward side of the frame so that its forward end lies at the side of the said typewriting machine, and capable of swinging back on its pivot substantially into the plane of said frame, and mechanism having a controlling member located on the forward end of said side arm, said mechanism maintaining operative connection with said marker in all positions of said arm, for moving the same downward to mark the lines.

14. In a typewriter's copy-holder to be placed at the back of a typewriting machine, the combination of a frame having a pair of posts located respectively on the right and left sides of the frame, a line marker guided on said posts, means carried by the posts for holding the frame in a substantially vertical plane, a side arm pivotally attached to one of said posts to swing on the axis of the same, said arm normally projecting forwardly from the forward side of the frame so that its forward end lies at the side of the said typewriting machine, and capable of swinging back on its pivot substantially into the plane of said frame, and mechanism having a controlling member located on the forward end of said side arm, said mechanism maintaining operative connection with said marker in all positions of said arm, for moving the same downward to mark the lines.

MABELLE M. HUNT.
